UNITED STATES PATENT OFFICE

128,672

DESIGN FOR A VAPORIZER

Edward Snyder, Chicago, Ill.

Application December 13, 1940, Serial No. 97,286

Term of patent 3½ years

To all whom it may concern:

Be it known that I, Edward Snyder, a citizen of the United States, residing at Chicago, in the county of Cook and State of Illinois, have invented a new, original, and ornamental Design for a Vaporizer, of which the following is a specification, reference being had to the accompanying drawings, forming a part thereof.

In the drawings:

Fig. 1 is a side elevational view of a vaporizer, embodying my new design.

Fig. 2 is the top plan view thereof.

Fig. 3 is the rear end view.

Fig. 4 is the front end view.

Fig. 5 is the bottom plan view.

I claim:

The ornamental design for a vaporizer, substantially as shown.

EDWARD SNYDER.
